Fig 3 is a view of a center piece with tube attached to convey the heated air from the back fire plate into the center piece.
Fig 4 is a view of a center piece with lateral opening for bringing the air through side plates directly into the center plate (not)
Fig 5 air enters front.

Witnesses,

J. S. Shattock
A. J. F. Turner

J. Johnson

✓. 15/11/2011.

BEST AVAILABLE COPY

Cook Stove.

No. 225.

(61.) Patented Mar. 22, 1859.

In Fig 1 air enters side plate of thin opening A, passes along fine plate B, up the connecting tube C into the center plates E & F, thence escaping through numerous small openings O, O, in Ring 3 as a stream of air out.

Inventor:
James Spear